JOHN ALFRED STEIN, OF NEW YORK, N. Y., ASSIGNOR TO AMERICAN MACHINE & FOUNDRY COMPANY, A CORPORATION OF NEW JERSEY

DOUBLE BELT CIGARETTE COLLECTOR

Application filed May 28, 1929. Serial No. 366,710.

This invention relates to cigarette collectors for continuous rod cigarette machines, and particularly to a collector for use with high speed machines of this type.

With the old slow speed machines, the cigarettes were collected by merely stopping them against a transverse wall as they came out of the machine, from which a crosswise belt carried them away. With the development of high speed machines from which cigarettes are delivered at the rate of 1200 to 1800 or more a minute at speeds of 330 to 450 or more feet per minute, this method has been found impractical, for the reasons among others that it results in injury to the ends of the cigarettes and also results in more or less uneven grouping due to erratic rebounding of the cigarettes.

The principal object of the present invention is to avoid such difficulties. To this end it is an object of the invention to provide means for reducing the speed of the cigarettes and forwarding the cigarettes at reduced speed. Still another object of the invention is to provide a cigarette collector which will group "tipped" cigarettes such as the well known cork tipped cigarettes, which ordinarily emerge from the cutoff with the tipped ends of alternate cigarettes adjacent each other, so that only cigarettes having their tips facing the same way will be grouped together.

Other objects are to produce a cigarette collector which will be reliable and efficient in operation over a wide range of cigarette machine speeds, including what according to present standards are very high speeds.

With these and other objects in view, the invention consists in certain constructions and combinations which will be hereinafter fully described and then specifically pointed out in the claims.

In the accompanying drawings which form a part of this specification and in which like characters of reference indicate the same or like parts:

Fig. 1 is a plan view, partly broken away, of a device constructed in accordance with the invention;

Fig. 2 is a side elevation, partly broken away, of the device shown in Fig. 1;

Fig. 3 is a cross section taken on the line 3—3 of Fig. 1;

Fig. 4 is a sectional view taken on the line 4—4 of Fig. 1; and

Fig. 5 is a sectional view taken on the line 5—5 of Fig. 2.

In carrying the invention into effect, there is provided mechanism for seizing cigarettes as they emerge from the cutoff of the cigarette machine and forwarding them at a given speed and alternately delivering them at separated positions, together with means for forwarding the cigarettes from said separated positions at reduced speed. In the best constructions, said mechanism includes two coating belts running over fixed and movable pulleys. Preferably, means are provided for oscillating these coating folding belts, which means, in the best form contemplated, consists of a slide supporting the movable pulleys and eccentric actuated means for reciprocating said slide.

The above means may be widely varied in construction within the scope of the claims, for the particular structure selected to illustrate the invention is but one of many possible concrete embodiments of the same. The invention therefore is not to be restricted to the precise details of the structure shown and described.

Referring to the drawings, the device selected for illustration is shown arranged to cooperate with the usual cigarette rod cutoff mechanism of a cigarette machine. Secured to the frame 6 of the cigarette machine is a bracket 7 carrying the cutoff mechanism. This bracket carries the main drive shaft 8 on which the rotating element 9 of the cutoff is supported. At its forward end the shaft 8 is provided with a gear 10 meshing with a gear 11 attached to a shaft 12 in the bracket 7. Concentric with the shaft 8 this bracket 7 supports a stationary gear 13 with which gear 14 of the cutoff meshes, thereby reciprocating the cutoff blade 15 by means, the details of which are not shown because not a part of the present invention. The other end of the shaft 12 carries the gear 16

driving through gear 17 the shaft 18 journaled at 19, which shaft serves as the drive shaft of the several parts of the cigarette collecting mechanism. Cooperating with the cutoff blade is the usual ledger plate 21, reciprocating on bar 22, provided with a guide tube 20 out of which the severed cigarettes emerge.

As the cigarettes emerge from the tube 20, they are caught and forwarded as follows: A stationary trough 24, wide enough to permit angular movement of a cigarette therein, and a leaf spring 23 resting lightly on the upper sides of advancing cigarettes 10 in the trough, guide the cigarettes into the bight of two coacting grooved belts 25 and 26 having parallel runs positioned to grip and forward cigarettes between their opposed grooved surfaces. These belts run over stationary pulleys 27 on studs 28 and over movable idle pulleys 29. These belts are driven at a speed slightly greater than that of the cigarette rod to thereby separate the cigarettes as they are forwarded. The studs 28 15 carrying the stationary pulleys are mounted in housings 31 and 32 fastened to studs 33 on the frame 6. Helical gears 34 mounted on the studs 28 mesh with gears 35 and 36 on the shaft 37, which shaft is connected by 20 coupling 38 to the shaft 39 in the bracket 40, this latter shaft being driven through gears 41 and 42 from the drive shaft 18.

In order to alternately deliver the cigarettes forwarded by the belts 25 and 26 at separated positions, the studs 30 carrying the movable idle pulleys 29 are reciprocated to oscillate the forwarding belts. This is brought about by mounting these studs on a slide 43 moving in a guideway 44 supported 25 by an arm 45, this slide being operated by a link 46 from an eccentric 47 on the drive shaft 18. The pulleys 27 and 29 of the belt 26 are adjustable toward and away from each other, to grip cigarettes with the desired firmness. 30 This is done by moving the housing 32 on studs 33 to adjust one of the pulleys 27 and by shifting stud 30 in block 43 to adjust one of the pulleys 29.

The alternate cigarettes thus delivered at 35 separated positions are forwarded at reduced speed, preferably about one-half of that of the belts 25 and 26, by the laterally spaced belts 48 and 49. At this reduced speed the cigarettes may be abruptly stopped for transverse delivery as hereinafter described, without injury. The belts 48 and 49 run over pulleys 50-51 and 50-52 respectively, the pulley 50 being a double one mounted on and driven by shaft 53 journaled at 54 on the arm 45. This shaft is coupled at 55 to a shaft 56 journaled at 57 and driven by means of gears 58 and 59 from the shaft 18. The idle pulleys 51 and 52 mounted on shafts 60 and 61 respectively are supported by the bracket 62 from the cigarette machine frame 6 and the

upper runs of the belts 48 and 49 are supported by a plate 63 having upstanding walls 64, 65, and 66 which extend along the sides of the belts and retain the cigarettes thereon. Plate 63 is suitably supported by the bracket 62 and by an angle piece 67. At the delivery end of each of the belts 48 and 49, curved deflecting plates 68 and 69 roll the cigarettes sidewise out of the path of the succeeding cigarettes and transversely extending walls 79 and 80 in the path of the cigarettes halt their longitudinal movement. The cigarettes from each of the belts 48 and 49 are received from the deflecting plates on the delivery belts 70 and 71 respectively, on which they are arranged side by side ready for removal and packaging. These belts are suitably driven by a drum 72 on a shaft 73 journaled in brackets 74 and 75 and driven from a shaft of the cigarette machine. The deflecting plates 68 and 69 are suitably supported by angle pieces 76 and 77 and a brace 78.

It will be seen that since alternate cigarettes only are received on each of the forwarding belts 48 and 49, the cigarettes need only be forwarded at a little more than one-half of the speed at which they are delivered from the cutoff. At this speed there is no danger of injuring the ends of the cigarettes when their longitudinal movement is halted and their rebound will be under sufficient control so that proper alignment and grouping on the delivery belts will not be interfered with. Also, since alternate cigarettes only are grouped on each of the delivery belts 70 and 71, tipped cigarettes which emerge from the cutoff with their tipped portions adjacent, will be delivered onto each belt with all of the tips on each belt pointing in the same direction.

What is claimed is:

1. A cigarette collector comprising mechanism seizing and forwarding cigarettes in a horizontal plane at a given speed and alternately delivering them endwise at separated positions, and means forwarding cigarettes from said positions at reduced speed.

2. A cigarette collector comprising mechanism seizing and forwarding cigarettes at a given speed and alternately delivering them at separated positions, and means forwarding cigarettes from said positions at reduced speed, said mechanism including two coacting belts running over fixed and movable pulleys.

3. A cigarette collector comprising mechanism seizing and forwarding cigarettes at a given speed and alternately delivering them at separated positions, and means forwarding cigarettes from said positions at reduced speed, said mechanism including coacting forwarding members, and eccentric-actuated means for oscillating said members.

4. A cigarette collector comprising mechanism seizing and forwarding cigarettes at a given speed and alternately delivering them

- at separated positions, and means forwarding cigarettes from said positions at reduced speed, said mechanism including two coacting belts, gear driven pulleys from said belts operative in fixed position, idle pulleys from 5 said belts, and means for reciprocating said idle pulleys.
5. A cigarette collector comprising mechanism seizing and forwarding cigarettes at a given speed and alternately delivering them 10 at separated positions, and means forwarding cigarettes from said positions at reduced speed, said mechanism including two coacting belts running over fixed and movable pulleys, a slide carrying said movable pulleys, an eccentric, and a link connecting said slide with 15 said eccentric.
6. A cigarette collector comprising mechanism seizing and forwarding cigarettes in a horizontal plane at a given speed and alternately delivering them endwise at separated positions, and means forwarding cigarettes from said positions at reduced speed, said means including two parallel belts receiving 20 cigarettes from said mechanism at said separated positions.
7. A cigarette collector comprising mechanism seizing and forwarding cigarettes in a horizontal plane at a given speed and alternately delivering them endwise at separated positions, and means forwarding cigarettes from said positions at reduced speed, said means including gear driven parallel belts receiving cigarettes from said mechanism at 25 said separated positions.
8. A cigarette collector comprising mechanism seizing and forwarding cigarettes at a given speed and alternately delivering them at separated positions, and means forwarding cigarettes from said positions at reduced speed, said mechanism including two coacting belts running over fixed and movable pulleys, a slide carrying said movable pulleys, an eccentric, and a link connecting 30 said slide with said eccentric, and said means including gear driven parallel belts receiving cigarettes from said mechanism at said separated positions.
9. A cigarette collector comprising mechanism seizing and forwarding cigarettes at a given speed and alternately delivering them at separated positions, and means forwarding cigarettes from said positions at reduced speed, said mechanism including a plurality 35 of coacting belts provided with grooved surfaces to effectively grip the cigarettes.
10. A cigarette collector comprising mechanism seizing and forwarding cigarettes at a given speed and alternately delivering them 40 at separated positions, and means forwarding cigarettes from said positions at reduced speed, said mechanism including a plurality of belts having parallel vertically disposed runs.
- 55 11. A cigarette collector comprising mech- anism seizing and forwarding cigarettes at a given speed and alternately delivering them endwise at separated positions, means for forwarding cigarettes from said positions at reduced speed, and convex deflecting plates 70 guiding said cigarettes.
12. A cigarette collector comprising mechanism seizing and forwarding cigarettes at a given speed and alternately delivering them at separated positions, and means forwarding 75 cigarettes from said positions at reduced speed, said means including a plurality of belts and a plate supporting said belts and provided with upstanding walls to retain the cigarettes on said belts.
- 80 13. A cigarette collector comprising mechanism seizing and forwarding cigarettes at a given speed and alternately delivering them at separated positions, means for forwarding cigarettes from said positions, and a plurality of delivery belts receiving cigarettes from said means, said means including a plurality of conveyor belts angularly disposed with respect to said delivery belts.
- 85 14. A cigarette collector comprising mechanism seizing and forwarding cigarettes at a given speed and alternately delivering them at separated positions, means for forwarding cigarettes from said positions, a plurality of delivery belts receiving cigarettes from said means, and a plurality of deflecting plates guiding cigarettes to said delivery belts, said means including a plurality of conveyor belts.
- 90 15. The combination with conveying means receiving cigarettes in a single line and having opposed moving surfaces gripping and forwarding said cigarettes between them, of means for oscillating said conveying means to deliver alternate cigarettes at transversely separated positions.
- 100 16. The combination with conveying means receiving cigarettes in a single line and having opposed moving surfaces gripping and forwarding said cigarettes between them, of means for oscillating said conveying means to deliver alternate cigarettes at transversely separated positions, and mechanism driving said means to move said surfaces at greater speed than that at which the cigarettes are received.
- 105 115 17. The combination with conveying means receiving cigarettes in a single line and having a pair of opposed belts for gripping and forwarding said cigarettes between them, of means for oscillating said belts to deliver alternate cigarettes at transversely separated positions, and means driving said belts at greater speed than that at which the cigarettes are received.
- 110 120 18. The combination with a cigarette conveyor having opposed moving surfaces for gripping and forwarding the cigarettes, of means for transversely reciprocating the delivery end of said means to deliver the cigarettes in a plurality of lines.
- 125 130

19. The combination with conveying means receiving cigarettes in a single line and having opposed moving surfaces for gripping and forwarding the cigarettes, of means for transversely reciprocating the delivery end of said means to deliver the cigarettes in a plurality of lines, said conveyor means including a pivotal mount at its receiving end.

In testimony whereof, I have signed my
10 name to this specification.

JOHN ALFRED STEIN.
